UNITED STATES PATENT OFFICE.

JOHN E. BELL, OF BROOKLYN, NEW YORK, ASSIGNOR TO THE BABCOCK & WILCOX COMPANY, OF BAYONNE, NEW JERSEY, A CORPORATION OF NEW JERSEY.

STEAM-BOILER.

1,215,765.

Specification of Letters Patent. Patented Feb. 13, 1917.

Application filed October 23, 1915. Serial No. 57,411.

To all whom it may concern:

Be it known that I, JOHN E. BELL, a citizen of the United States, residing at New York city, borough of Brooklyn, in the county of Kings and State of New York, have invented certain new and useful Improvements in Steam-Boilers, of which the following is a specification.

My invention relates to a construction and arrangement of water boxes at the rear of a chain grate stoker, and will be understood by reference to the accompanying drawings in which Figure 1 is a vertical longitudinal section through a steam boiler showing my invention applied thereto; Fig. 2 a front view showing two of the boiler drums, the water boxes and their connections with the drums; and Figs. 3 and 4 enlarged side and end views of the water boxes. Similar reference numerals indicate similar parts in the several views.

I have shown one application of my invention in connection with a steam boiler of the Stirling type having three upper steam and water drums 1, 2 and 3; a lower mud drum 4; and connecting banks of generating tubes 5, 6 and 7. Any suitable baffling to direct the flow of the gases over and along the tubes may be employed. A superheater 8 may be placed in the secondary combustion chamber at the rear of the front bank of tubes.

The boiler shown is fired by a chain grate stoker 9 of any approved construction. At the rear of the stoker is a bridge wall 10 built up from the floor to the mud drum 4 and having an extension 11 projecting up to an intermediate portion of the front bank of tubes. The upper part 11 of the bridge wall projects over the rear of the stoker, and in the space between said part of the bridge wall and the stoker I have arranged two water boxes 12 and 13, one above the other. These boxes extend from side to side of the furnace, as shown in Fig. 2, and have independent connections with the boiler circulation. The upper box 12 is connected to the mud drum 4 by a pipe 14, entering at one end of the box, and to the front drum 1 by a pipe 15 leaving the other end of the box. Similarly the box 13 is connected to the mud drum by a pipe 16, and to the front drum 1 by a pipe 17. The pipes 15 and 17 are extended in front of the upper part or extension

11 of the bridge wall and are then bent into parallelism with the tubes of the front bank 5.

The upper water box 12 is square or rectangular in section, and the lower water box is curved and preferably circular in section. The function of the former is to protect the top of the lower box from being overheated by the radiant heat of the furnace, and also to serve as an additional amount of cool surface to which the clinker will not become attached. Where a circular water box is used alone the top must be protected from the radiant heat by brickwork, and to make this protection efficient the brickwork must extend well over the top of the box, and with the box so protected the slag and clinker which accumulates on the brickwork, will extend downward and interfere with the operation of the box. By protecting the top of the lower curved or circular box from the radiant heat by a second water box, the trouble due to the action of slag and clinker is eliminated. The cylindrical lower water box is so placed above the rear of the stoker that it will crush the ash and clinker to a substantially uniform thickness.

A cylindrical box is better than a square or rectangular box for this purpose as it serves to crush down or plane out the ash and clinker by gradually reducing its thickness as the ash and clinker travel beneath it, whereas a rectangular or square box does not produce a crushing action on the ash and clinker but serves simply as a dam or obstruction. If a rectangular or square box is set high enough to prevent trouble through the formation of a mass of unburned coal and clinker in front of it, the lower part of the fire may pass beneath the box with but little retardation. By employing a circular box the entire bed of fire is retarded and the trouble through the accumulation of clinker at the front of the box is minimized.

It is further important that the boxes be so connected to the boiler circulation that any difference in their length due to expansion, which may result when starting up a cold boiler through a difference of temperature of the boxes, will not result in undue strains at the joints and consequent leakage. In my construction this feature is covered by providing separate inlet and outlet con-

nections for the boxes, thereby avoiding nippled connections between the boxes.

In my construction the inlet connections to the boxes are protected from the heat of the fire and the outlet connections are exposed to the heat of the furnace, both of which features are highly desirable in an arrangement of the sort. Exposing the outlet connections to the heat of the fire increases the rapidity of the circulation and adds to the effectiveness of the arrangement.

What I claim and desire to secure by Letters Patent of the United States is:—

1. A steam boiler furnace comprising a chain grate stoker, a bridge wall, and two water boxes placed one above the other at the rear of the stoker, the lower of said boxes being curved in section and the upper square or rectangular in section, said boxes being connected at one end to the mud drum and at the other end to a steam and water drum.

2. A steam boiler furnace comprising a chain grate stoker, a bridge wall and two water boxes placed one above the other at the rear of the stoker, each box having a separate inlet connection from the boiler mud drum at one end and a separate outlet connection leading to the steam and water drum at the other end.

3. A steam boiler furnace comprising a chain grate stoker, a bridge wall and two water boxes placed one above the other at the rear of the stoker, each box having a

separate inlet connection from the boiler mud drum at one end and a separate outlet connection leading to the steam and water drum at the other end, the inlet connections being protected from the heat of the fire.

4. A steam boiler furnace comprising a chain grate stoker, a bridge wall and two water boxes placed one above the other at the rear of the stoker, each box having a separate inlet connection from the boiler mud drum at one end and a separate outlet connection leading to the steam and water drum at the other end, the outlet connections being exposed in part or in whole to the heat of the furnace.

5. A steam boiler furnace comprising a chain grate stoker, a bridge wall having a portion thereof extending over the rear of the stoker, and two water boxes placed one above the other in the space between the stoker and the overhang of the bridge wall, the lower of said boxes being curved in section and the upper square or rectangular in section, said boxes being connected at one end to the mud drum and at the other end to a steam and water drum.

In testimony whereof I have hereunto signed my name in the presence of two subscribing witnesses.

JOHN E. BELL.
